UNITED STATES PATENT OFFICE.

EARL F. BALDWIN, OF GARDNER, MASSACHUSETTS, ASSIGNOR TO AMERICAN FIBRE CORPORATION, OF GARDNER, MASSACHUSETTS, A CORPORATION OF MASSACHUSETTS.

LOOM.

Application filed December 12, 1921. Serial No. 521,624.

This invention relates to looms having been more particularly designed for weaving fiber such as strands formed from paper strips.

1. One feature of the invention relates to a novel construction and arrangement of pick-laying members which for convenience I have termed "pickers," two being employed, one carrying the strand half way through the shed and presenting it to the other which takes hold of the strand and carries it the remaining distance while the first picker leaves the shed.

2. Another feature relates to a novel means for cutting off each pick or filling strand while the pickers are retracted.

20 A further feature relates to mechanism for feeding a filling strand of indeterminate length to the pickers which grasp the end thereof and carry it through the shed, this feed being continuous, whereby sufficient slack is produced when the pickers are retracted to avoid a destructive jerk on the strand as the succeeding pick is being laid.

25 3. A further feature relates to a novel construction of harness by which the gripping of the pick by the warp strands or threads may be caused to occur progressively from or toward the center or edges of the fabric 30 width, as may be desired in accordance with the condition of the fiber.

35 Still another feature of this invention relates to improved tension mechanism for the warp strands by which each strand is separately tensioned but all are allowed to move as a unit during the shedding.

40 4. This invention also provides a take-up mechanism so designed as to cause no bruising or injury to the strands in the woven fabric. This mechanism is further so designed as to be adjustable to vary the rate of feed while the machine is running.

45 Further objects and advantageous details and combinations of parts will appear from a more complete description of an embodiment shown in the accompanying drawings in which

50 Figure 1 is a front elevation of the central portion of the machine partly broken away.

55 Figure 2 is a front elevation on the left hand end of the machine.

Figure 3 is a similar view of the right hand end.

55 Figure 4 is a left end elevation.

Figure 5 is a right end elevation,

Figure 6 is a section on line 6—6 of Figure 1.

Figure 7 is a section on the line 7—7 of Figure 1.

Figure 8 is a section on line 8—8 of Figure 1.

Figure 9 is a section on line 9—9 of Figure 1.

Figure 10 is an elevation of the harnesses and immediate mechanism.

Figure 11 is a view along the line 11—11 of Figure 10, but showing the warp threads in position.

Figure 12 is a view partly in section of a right hand picker mechanism.

Figure 13 is a similar view of a left hand picker mechanism.

Figure 14 is a fragmentary view showing the pickers in their central mating positions.

75 Figures 15 and 16 are detail elevations showing a different form of picker in open and closed positions.

Figures 17 and 18 are similar views of another form of picker.

Figures 19 and 20 are similar views showing a further modification of the picker.

Figure 21 is a section on line 21—21 of Figure 16.

Figure 22 is a top plan of the picker ends 85 of the form shown in Figures 15 and 16 and 19 and 20.

Referring first to Figures 1, 2, and 3 the machine as shown comprises a pair of spaced vertical frame members 1 and 2 between 90 which the fabric is woven. These frame members are supported from end base sections 3 and 4 which extend outwardly from the frames 1 and 2 and which carry at their outer ends vertical standards 5 and 6 which carry at their upper ends guide frames 7 and 8 for the slidable reception of the pickers. Each frame 7 and 8 comprises a pair of parallel spaced elements 9 and 10 having their opposed faces grooved to receive shoes 100 11, 12, 13, and 14 which are pivoted on studs 15 to the outer ends of the pickers, the left hand picker being indicated in Figure 2 at 16 and the right hand picker indicated in Figure 3 at 17. The guide members 9 and 10 are fixed to the forward face of plates 20 by which they are held in proper relative positions. The pickers 16 and 17 are reciprocated between the guideways 9 and 10 in opposite directions in unison. For this pur- 110

pose the base frames 3 and 4 have pivoted thereto arms 25, the pivotal connection preferably consisting of bolts 26 adjustably fixed in guideways 27 at the bases of the portions 5 3 and 4. The upper end of each arm 25 is connected by a link 26 pivoted at opposite ends to one of the arms to its respective picker 16 or 17. These arms 25 are swung about their pivots 26 by means of a pair of 10 eccentrics 27 and 28, the straps 29 and 30 of which have fixed thereto rods 31 pivoted at their outer ends at 32 to the arms 25. In order to adjust the extent of swing of these arms it is preferable to mount each pivot 32 15 in a slotted portion 34 which may, if desired, be formed on a socket member 35 which receives the lower end of the corresponding arm 25. With this construction the socket member may be of metal while the arm itself 20 may be of wood to lighten the construction.

The eccentric 27 is fixed to a shaft 40 journaled in a pair of pedestals 41 (see Figure 4) extending upwardly from a platform 42 mounted on the base 3. Between the 25 bearings 41 the shaft 40 has fixed thereto a beveled gear 43 which meshes with a similar gear 44 fixed to a shaft 45 which extends substantially the length of the machine and is the main driving shaft. This shaft is 30 journaled outwardly of the frame members 1 and 2 in pedestals 46 and 47 (see Figures 2 and 3). Beyond the pedestal 47 shaft 45 carries a bevel gear 48 meshing with a similar gear 49 on a shaft 50 which carries the 35 eccentric 28. The shaft 50, as shown in Figure 5, is journaled in pedestals 51 similar to the pedestals 41 and which are carried on a platform 52 surmounting the base block 4.

The shaft 45 inwardly of the pedestal 47 has fixed thereto a gear 60 with which meshes a pinion 61 (see Figure 5) carried by a jack shaft 62, this shaft being journaled in pedestals 63. This shaft 62 has journaled 40 thereon a gear 64 which forms one element of a clutch. Any suitable form of clutch may be used but as shown a clutch of the expanding ring type is used, being indicated in outline at 65 and having an actuating arm 66 by which it may be expanded to clutch the gear 64 to the jack shaft 62. For actuating this arm a cone collar 67 is shown as 45 slidably mounted on the jack shaft, the conical face thereof engaging the end of the arm 66. This collar may be moved lengthwise on the shaft by means of a forked arm 68, the forks thereof engaging in a peripheral groove 69 in the collar, this arm being fixed to one end of an actuating rod 70 which is 50 slidable through the end frame or wall 2. At its inner end it is pivoted to the end of an arm 71 (see Figures 3 and 9) which is fixed to a rock shaft 72 journaled in bearing brackets 73 fixed to the inner face of the wall 55 2. At its opposite end rock shaft 72 has

fixed thereto an arm 74 and to the upper end of this arm is pivotally attached a reciprocable clutch shipper rod 75. This rod 75 extends across the machine and through the frame member or wall 1 and outwardly 70 thereof is pivoted at 76 (see Figures 2 and 4) to an actuating lever 77. This actuating lever is pivoted at its lower end to a bracket 78 fixed to the outer face of the frame member 1 and extends upwardly and terminates 75 in an actuating handle 79 which is positioned near the upper forward edge of the frame member 1. This lever may be guided in its movements by means of a slotted bracket 80 fixed to the outer face of the frame member 1. It will be seen therefore that the clutch is actuated from the opposite end of the machine where it is convenient to the operator as will be later described.

The gear 64 on the jack shaft is driven 85 through an idler gear 80 suitably supported from a bracket 81 by a pinion 82 fixed to the shaft 83 of an electric motor 84, this motor being mounted on a bracket 85 extending rearwardly from the base member 4. 90

Pickers.

As before stated the pickers are intended to move in opposite directions to meet substantially centrally of the fabric and then 95 to retract therefrom. The filling strand, as shown at 90 in Figure 2, is presented through a filling paying out mechanism which will later be described, to the left hand picker. The strand is engaged by this 100 picker when in its retracted position so that on its advance to meet the other picker the strand is carried substantially half way through the shed and presented to the other picker which thereupon seizes the end thereof while the left hand picker releases the strand. As both pickers are then retracted the strand pays out through the left hand 105 picker and is carried the remainder of the distance through the sheds by the right hand picker, the picks thus being laid in the shed. A cutting mechanism, to be described, then severs the strand adjacent the left hand 110 picker which grips the material again for the laying of a subsequent pick in the same manner. Certain pickers designed to function in this manner are shown in detail in 115 Figures 12 to 22.

Referring to the form shown in Figure 120 13, which illustrates one form of left hand picker indicated in Figure 2 at 16, forwardly of the pivots 15 the picker comprises a bar formed as a tube 95 having fixed at its outer end a strand guide 96. This guide comprises a nozzle portion 97 fixed in the end of a plug 98 which closes the outer end of the tube. The plug 98 is perforated centrally in alignment with the nozzle perforation for the passage of the strand and has 125 projecting rearwardly therefrom a tubular 130

extension 99 terminating in a beveled end 100. The tube 95 is slotted at 101 for the passage of the strand and has slidable therein a guide block 102. One end of this guide block has fixed thereto the inner ends of a pair of clamping bars or jaws 103, 104, the jaw 103 having a slot 105 therethrough through which the strand may be passed to be gripped between the ends of the bars in alinement with the nozzle 97. The forward ends of the bars 103, 104 are beveled as shown at 106 and 107 so that by sliding the block 102 towards the nozzle, these ends may impinge on the beveled end 100 and be wedged apart to release the strand, such action being indicated in the left hand portion of Figure 14, and by sliding the block 102 rearwardly the ends of the bars 103 and 104 slip off the portion 99 and resume their closed position as shown in Figure 13.

For actuating the clamping jaws in this manner, the guide block 102 has fixed thereto a rod 108. This rod is preferably threaded into the block 102 as shown at 109, a check nut 110 being provided by which the effective length of the rod 108 may be adjusted and fixed. This rod 108 extends through the tube 95 and extends through a guide portion 111 fixed on the forward face of a block 112 which carries the pivots 15 for the guide shoes 11, 12, 13, and 14. Outwardly of the guide 111, the rod 108 has fixed thereto a forked member 113 between the arms of which is pivoted the lower end of a lever 114 fulcrumed on a bolt or pin 115 carried at the upper end of an arm 116 extending from the block 112. The upper end of the lever 114 terminates in a rounded head 117 which, as shown in Figure 2, is designed to impinge on a pair of abutments 118 fixed to the guide member 9 near the limits of traverse of the arm 116. When the head 117 impinges on the left hand abutment it is evident that the lower end of the lever 114 is rocked outwardly, thus retracting the jaws 103 and 104 from the portion 99 and permitting them to grasp a strand, while engagement of this head with the right hand abutment 118 rocks the lever in the other direction to force the ends of the jaws 103 and 104 on to the portion 99 to release the strand. This picker being in the position shown in Figure 2, therefore, the jaws may grip the strand preparatory to carrying it into the shed. The strand is first threaded between these jaws, preferably before the complete retraction of the picker so that the jaws are open, the strand extending outwardly through the nozzle 97. As the picker completes its outward movement, the jaws engage the strand and pull it backwardly so that its end retracts within the nozzle. On inward motion of the picker the strand is carried within the shed to the opposite pick-

er but at the extreme inward motion thereof the end of the strand is projected from the nozzle and then released from this picker by engagement of the lever 114 with the right hand abutment 118. On subsequent retraction of this picker toward the position shown in Figure 2, the strand may therefore be pulled through the picker which is released therefrom.

The right hand picker, which receives the strand from the left hand picker, may be constructed as shown in Figure 12. As there shown it comprises a tube 120 having at its inner end a conical hollow socket 121 within which the nozzle 97 of the left hand picker may project as shown in Figure 14. This member 121 has projecting from its rearward end a tubular extension 122 terminating in a beveled end 123. Slidable within the tube 120 is a block 124 having fixed at its outer end a pair of bars or jaws 125, 126 similar to the jaws 103 and 104, except that neither is slotted for the passage of the strand. Those jaws may be separated to release the strand by movement of the block 124 in a direction to carry their ends into contact with the beveled end 123, these jaws being provided with mating beveled ends 125' and 126' to cause them to ride up over on to the portion 122. They may be moved to grip the strand by sliding the block 124 in the opposite direction, allowing their inner ends to slip off the portion 122. For actuating the block 124 in this manner a rod 128 is adjustably fixed therein and held in adjusted position by means of a lock nut 129. This rod extends through a guide 130 fixed to the forward face of a block 131, similar to the block 122, and has fixed at its end a forked member 132 between the arms of which is pivoted at 133 a lever 134 fulcrumed at 135 to the block. It will be noted that while the lever 113 is of the first class, lever 134 is of the second class. This lever 134 extends upwardly toward the right hand guide member 9 and impinges near opposite ends of the stroke of this picker on abutment brackets 136. As the lever impinges on the left hand bracket 136, as the pickers come together (see Figure 14), this lever is rocked rearwardly, thus retracting the rod 128 and removing the jaws 125 and 126 from the portion 122, permitting them to engage the strand presented thereto by the left hand picker as shown in full lines in Figure 14, the position of the parts just prior to this position being shown in dotted lines in this figure. As the pickers retract, the strand is therefore pulled through the left hand picker until the pickers have nearly reached their limit of motion. At this time the lever 134 impinges on the right hand bracket 136 and is rocked forwardly by the continued outward motion of the picker, pushing the rod 128 in-

wardly and causing the jaws 125 and 126 to ride up on the member 122 and release the strand, this action taking place substantially simultaneously with the gripping of the strand by the left hand picker.

In Figures 15, 16, 21 and 22 is shown a modified form of picker which may be used in place of the left hand picker 16. In this construction in place of the tube 95 is employed a pair of spaced spring bars 140 and 141. The outer ends of these bars are bent toward each other and terminate in gripping jaws 142, 143 which are preferably serrated in order to obtain a better grip on the strand. These jaw portions are offset laterally from the remainder of the bars 140 and 141 as shown in Figure 22 and the member 142 is provided with ears 144, depending on either side of the portion 143 in order to prevent the lateral escape of the strand from between the jaws. Positioned back of the jaws the bars 140 and 141 have fixed thereto cam plates 146 and 147, each cam plate having an angular hump 148 thereon. Positioned between the plates 140, 141 is a wedge cam member 149 fixed at its rear end by a threaded connection to a rod 150, this rod corresponding in action and position to the rod 108 shown in Figure 13 and which is made fast at its outer end in the same manner to the lower end of the lever 114. The cam member 149 is notched to form a larger substantially diamond shaped portion 151 and outwardly thereof a smaller similar portion 152. When the cam member is positioned so that the humps 148 bear between these portions 151 and 152, the clamping jaws 142 and 143 close together as shown in Figure 15. When, however, the cam member is moved inwardly to the position shown in Figure 16, the humps 148 bearing forwardly of the portion 151, the jaws are opened. Since the bar 150 is actuated by the lever 114 these jaws are caused to grip the strand at their extreme retracted position and to release the strand when the picker is moved forwardly, having laid the strand half way through the shed. The strand is then seized by a picker, the end of which is shown in Figures 19 and 20. Referring to these figures, parallel spaced spring bars 160 and 161 are bent toward each other at their outer ends to form jaws 162 and 163 similar to the jaws 142 and 143, the jaw 162 having side plates 164 enclosing the side edges of the jaw 163. Rearwardly of these jaws, bars 160 and 161 are provided with cam humps 165 and cooperating therewith is a cam member 166 having a pointed end 167 and a pair of oppositely disposed recesses 168 back of the point. Connected to the cam member 166 is an actuating rod 170 which is connected similar to the rod 128 of the form shown in Figure 12 to the actuating lever 134. In the

position of the parts as shown in Figure 19, the cam member 166 is retracted so that the humps 165 are adjacent the point 167 so that the jaws 162 and 163 may close together. When the rod 170 is pushed inwardly to bring the depressions 168 opposite the cam humps 165, the jaws are opened as shown in Figure 20. As the rod 170 is actuated by the lever 134 these jaws are closed when the picker is at its inward limit of motion adjacent the end of the left hand picker to take the strand therefrom and are opened as this picker reaches the extreme outward limit of motion.

In Figures 17 and 18 is shown a still further modification of the left hand picker in which the jaw 142' has no side plates 144 overlapping the lower jaw, but instead is provided with a strand receiving eye extending longitudinally thereof as at 171. The mating jaw 143' is slotted to receive the eye member 171 and has a toothed projection 173, which when the jaws are close together, passes through an opening 174 in the eye member and serves to clamp the strand against a mating serrated portion 175 within the eye. The rear end of the eye terminates in an outwardly flared portion 176 so that the strand may be fed readily into the eye. These jaws may be actuated by a cam member 149 in the manner described in connection with Figures 15 and 16. The jaws are offset from the body of the spring bars in each instance as shown in Figure 22 in order to make the threading of the strand therein by the operator an easy matter.

The form of pickers shown in Figures 12 and 13 is particularly adapted for wet or soft material, since the end of the strand does not project from the left hand picker while it is being carried into the shed until it is within the nozzle-receiving socket almost in position to be grasped by the right hand picker. Its proper presentation for grasping by the receiving picker is then assured.

Filling strand cutting mechanism.

After the laying of each pick the strand is cut adjacent the end of the left hand picker so that when the beater, to be described, has pushed the pick into position, a new strand may be laid. This cutting off mechanism is shown in Figures 1, 2, and 6. Referring to Figure 6, it comprises a pair of bars 180 and 181 which are slideable side by side in a vertical guide 182 fixed to the inner face of the frame member 1. The upper end of the bar 180 has a lateral jaw extension 183 to which is made fast a knife 184 which is positioned directly above a corresponding cooperating knife 185 fixed to the upper end or jaw of the slide 181. The slides 180 and 181 are held in position in the guide 182 by retaining plates 186. The lower end of this guide has fulcrumed thereon at 187

a cam lever 188 and a pair of links 189 and 190 are pivoted at their lower ends to the ends of this cam lever and at their upper ends at 191 and 192 to the slides 180 and 181. By rocking of this cam lever it is therefore evident that the bars 180 and 181 may be reciprocated in opposite directions to cause the knives 184 and 185 to approach and recede from each other. These bars are so actuated by means of a cam 193 fixed to a shaft 194, this cam having a hump 195 thereon which is movable to engage a roller 196 journaled on the lever 188. This roller is urged downwardly toward the cam by means of a spring 197 engaging at its upper end over the pivot 192 and at its lower end over the pivot 187, this spring therefore tending to keep the bar 181 in its lowered position. In order to prevent wear of the parts the cam lever 169 is held slightly above the surface of the cam 193 except when the hump 195 is active. For this purpose a stop 198 adjustably carried by a bracket 199 fixed to the inner face of the frame member 1 is positioned to be impinged by the lower outer end of the lever 188 to limit the downward motion of this arm. The hump 195 with the cam 193 is so positioned as to raise the roller 196 and actuate the cutters with a sudden movement as the left hand picker 16 is in its retracted position. The knives then part and the picker in its inward motion passes immediately therebetween. The shaft 194 is also designed to actuate the beater elevator shaft in a manner which will be later described. This cutting mechanism is not claimed *per se* herein, being claimed in my divisional application Serial No. 194,866, filed May 28, 1927, for strand severing mechanism.

Shedding mechanism.

Positioned between the frames 1 and 2 back of the paths of the pickers is the shedding mechanism. As shown more clearly in Figure 10 this mechanism comprises a series of harness frames which are positioned in pairs end to end as shown at 200, 201 and 202, 203, 200 and 201 being the forward frames and 202 and 203 the rearward frames. These frames carry the heddles for controlling the motion of the warp threads or strands in the usual manner, these being indicated for the forward frames at 204 and 55 for the rearward frames at 205. By relative up and down movement of these frames the shedding action is caused to take place.

As when the fiber for which this machine is designed is dry it is brittle, this invention provides means whereby the shedding may take place progressively between the center and edges of the fabric. By this means the pick as laid is gripped by the warp strands near the center of the fabric 65 as it is being beaten into place so that it may

draw inwardly toward the center to conform to its crimped condition in the finished fabric, this condition being caused by passing alternately over and under the warp strands. As the shedding takes place progressively the crimping also takes place progressively and avoids the liability of breaking the strand due to the tension imposed thereon by this action. Should the strand be wet, however, and in somewhat soft condition, it is possible to change the sequence of shedding so that crimping by the warp strands takes place progressively from the edges of the fabric toward the center. This progressively grips the pick from its ends inwardly, preventing the drawing inwardly thereof and causes the strand to be stretched as it is beaten into place. For the purpose of effecting this progressive action the harness frames are formed in a pair of sections, 70 positioned end to end across the width of the fabric as just described so that the timing of the shedding between the center and the sides of the fabric may be varied. For the purpose of actuating these frames in 75 this manner, each frame has depending from its lower edge adjacent its end, an arm 206 to the lower end of which is pivoted, as shown in Figures 1 and 9, the upper end of a bar 207. These bars are made fast at their 80 lower ends in eccentric straps 208 of eccentrics 209 fixed to rotate with a shaft 210 which extends through the end frames 1 and 2. Positioned intermediate these frames is a bracket 211 arranged parallel 85 therewith and in opposite side faces of this bracket and on the inner faces of the frames 1 and 2 are vertical guides 212 for guiding the several frames in their vertical movement. The bracket 211 is supported from 90 a longitudinal frame member 213 which ties the frame members 1 and 2 together adjacent their upper rear corners, a similar member 214 being employed adjacent the lower rear corners. Beneath the bracket 100 211 a bracket 215 having bearings for the various operating shafts is placed and is supported at its forward end on a front frame member 216.

The eccentrics for actuating opposite ends 105 of each mating pair of harness frames may be adjusted so as to cause the mating inner ends of these frames to move somewhat ahead or behind the outer ends of these frames the stroke of both ends having the 110 same amplitude. This causes the shedding to take place progressively as indicated in Figures 10 and 11 where it is noted that the openings in the heddles 204 and 205 are more widely spaced centrally where the pairs 115 of frames meet than at their ends indicating that the shedding is nearer complete at that point than at the sides of the fabric. This is indicated in Figure 11 wherein the strands are controlled by the front and back harness 120

125 130

frames 201 and 203, are more widely spaced than the strands *b*, *b*, *c*, *c*, *d*, *d*, *e*, *e*, positioned progressively further from this point and nearer one side of the fabric. This causes the pick, indicated in section at *x* in this figure to be more tightly engaged by the strands *a*, *a* than the remaining strands which are progressively less in engagement as they are further away from strands *a*.

10 As the two ends of these frames have the same amplitude of motion, however, it is evident that the strands *b*, *c*, *d*, and *e* will successively assume as wide open a position as the strands *a* but at a later period. This

15 progressive action is believed to be broadly new and is regarded as a valuable feature of this invention since it permits fiber of various degrees of dryness to be handled successfully, allowing the tension exerted

20 thereon to be regulated to accomplish the best results. As shown in Figures 1 and 9 the shaft 210 which actuates the harnesses is driven from the main shaft 45 by means of a gear 217 thereon meshing with a pinion 218 fixed to the shaft 45.

The shedding mechanism per se is claimed in my divisional application Serial Number 603,340, filed November 25, 1922, for harness mechanism for looms.

30 *Warp tension mechanism.*

Because of the progressive action of the harness mechanism causing progressive shedding, the warp threads must be drawn through the tension mechanism at somewhat different times. For this purpose means for applying tension individually to the warp strands has been provided. As shown in Figures 4, 5, 6, 7, 8, and 9, between the end frames 1 and 2 is positioned a bar 220 of somewhat T-shape in cross section. Passing through the end frame members 1 and 2 are bolts 221 and 222 (see Figures 4 and 5) which engage within suitable sockets in the ends of the bar 220 and serve to pivotally mount this bar. Seated on the upper face of the bar 220 is a bar 223 having a series of openings 224 therethrough, one for each strand of warp material and positioned back of each opening 224 is an eye 225 flared outwardly at its rear end through which the strands may be threaded. Within each recess or opening 224 is pivoted a tension lever 226, the inner end of which is urged downwardly toward the bar 220 to engage on the strand by means of a spring 227 seated in a socket 228 thereabove and the tension of which may be adjusted by means of a plug 229 threaded in the upper end of this socket.

50 By grasping the upper end of lever 226 it may be rocked upwardly out of engagement with the strand so that the strand may be fed therethrough by hand as in threading the machine. Extending from opposite ends

55 of the bar 223 are arms 230 which project

forwardly over the frame portions 1 and 2 and terminate in vertically disposed socketed portions 231 within which are housed coil springs 232 which bear on the upper faces of the frame portions 1 and 2. The tension on these springs may be regulated by means of screw rods 233 threaded through the upper ends of the portions 231 and having lock nuts 234 thereon for fixing them in adjusted position. The extent to which these arms 75 230 may be swung downwardly toward the upper faces of the frame portions 1 and 2 is adjustably fixed by means of rods 235 threaded through lugs 236 extending forwardly of the portions 231 and striking at 80 their lower ends on the frames. Lock nuts 237 may be employed to fix these studs in adjusted position. As the tension elements 226 engage the strands above the pivot bolts 221 and 222 tension exerted on the strands 85 forwardly through the harnesses tends to rock the arms 231 downwardly as far as permitted by the stop studs 235. The springs 232, however, are designed to be much heavier than the tension springs 228 90 for the individual strands so that the bar will yield as far as permitted by the studs 235, only when all the strands are tensioned at a point not quite sufficient to permit them to feed through their individual tensioning devices. Tension applied to a few strands causes them to pay through their individual tension devices without moving the bar. This permits a yielding of the tensioning device as a whole to the tension caused by 100 the shedding motion of the harness frames and permits each strand to pay out as it is additionally tensioned due to the progressive shedding action to effect a substantially uniform tension on all the strands, the 105 springs 232 acting as master springs for the entire set of warp strands.

This warp tension mechanism is claimed in my divisional application Serial Number 603,339, which eventuated March 10, 1925, 110 into Patent No. 1,529,417, let-off mechanism for looms.

115 *Filling feed mechanism.*

The filler feed mechanism is driven from the main shaft 45 by means of a gear 240 (see Figure 9) fixed to this shaft and meshing with a pinion 241 fixed to a shaft 242. This shaft extends between the frame members 1 and 2 and through the frame member 1, 120 on the outer face of which it carries, as shown in Figure 4, a friction wheel or disk 243. Positioned diametrically across the face of the disk 243 is a shaft 244 which is journaled at its opposite ends in bearings 245 which are pivotally mounted on vertical pivots 246. Shaft 244 is threaded as indicated at 247 for the reception of a pair of threaded collars 248, each collar having a series of openings 249 therein for the recep- 130

tion of a spanner wrench by which they may be rotated. These collars are adapted to clamp between them a friction wheel 250 having a frictional peripheral face 251 of yielding material which bears on the face of the friction disk 243. The bearings 245 before mentioned are positioned so as to urge the wheel 251 against the face of the disk 243, the shaft 244 flexing slightly for this purpose. Because of this flexing of the shaft 244 the bearings 245 are pivotally supported. Adjacent the forward bearing 245 the shaft 244 carries a grooved wheel 252 about which the strand 90 may pass being led thereto through an opening in a guide plate 253 positioned near the lower edge of this wheel. The strand passes about this wheel 252 and beneath a narrow roller 254 which bears against the upper face of the strand. This roller 254 is carried by a lever 255 pivoted at 256 (see Figure 2) to a portion of the plate 253, the inner end of this lever bearing on a plunger 257 seated in a vertical socket 258. The roller 254 may be urged into engagement with the strand by means of a spring (not shown) seated within the portion 258 and bearing against the pin 237. This construction insures a frictional feed for the strand, the rate of this feed being adjustable by adjusting the position of the friction face 251 radially of the disk 243, it being fixed in adjusted position by tightening the collars 248 thereagainst. It will be noted that a filling strand of indeterminate length is thus presented to the left hand picker continuously so that as this picker starts to carry the end of the strand into the shed, after the cutting of the strand has been effected, the strand is slackened sufficiently between the picker and the bight between the roller 254 and wheel 252 to avoid any sudden jerk thereon which might cause breakage or overrunning of the reel (not shown) which may be used to carry the filling strand.

Beating mechanism.

After the pick has been laid in the shed it is beaten up against the completed fabric by means of a beater which comprises a bar 270 having upstanding therefrom a series of teeth 271 which extend between the strands of warp material. The bar 270 extends between the frames 1 and 2 and is mounted to slide on a pair of arms 272 which are fixed to a rock shaft 273 journaled in the frames 1 and 2 and also in a bracket 274 extending upwardly from the intermediate bracket 215. The slidable mounting of the bar 270 is by means of frames 275 slidable along the arms 272 and to the rear ends of which the bar is made fast. The rear ends of the arms 272 are rocked upwardly to bring the teeth 271 in position between the warp strands and downwardly to remove them from oper-

ative relation thereto by means of a pair of cams 276 (see Figures 1, 7, and 8) which are fixed to the shaft 194 which actuates the filling strand cutter and which is journaled in the frames 1 and 2 and in the intermediate bracket 215. The cams 276 are face cams, each having a cam groove 278 within which rides a follower 279 fixed to a yoke member 280. This yoke member is forked at its lower end 281 to take over the shaft 194 in order to guide the yoke in its motion. The upper end of this yoke is attached by means of a bar 282 to the rear end of each arm 272. The shaft 194 is driven by a gear 283 meshing with the gear 217 fixed to the shaft 210. The slide frames 275 are reciprocated on the arms 272 by means of a pair of arms indicated at 285 which are pivoted at their upper ends to links 2850 pivoted to the frames and at their lower ends intermediate the ends of tie brackets 286 which extend across between the frame members 214 and 216 by means of pivot pins 287. Arms 285 are rocked forwardly and rearwardly by means of a pair of cams 290 which are fixed to a shaft 291 journaled at its ends in the frames 1 and 2 and at its central point in a tie member 292 (see Figure 8) joining the back frame members 213 and 214. As shown in Figure 9 this shaft 291 is driven from the main shaft 45 by means of a gear 293 thereon meshing with a gear 240. Each of the cams 290 has a cam groove 294 in one face within which rides a follower 295 carried at the rear end of an arm 296 slotted at 297 to receive therethrough the shaft 291, and which is pivoted at its forward end 298 to one of the arms 285. With this construction after the pick has been laid the bar 270 is raised upwardly to bring the teeth 271 between the strands of warp material and is moved to beat the pick up against the woven fabric.

Fabric take-up.

After being beaten the fabric passes over the take-up mechanism which comprises an upper roll 300 over which the fabric passes, a roll 301 beneath roll 300, under which the fabric passes, and roll 302 in horizontal alignment with roll 301 over which the fabric passes. From the roll 302 the fabric passes downwardly to the arbor or mandrel 303 on which it is wound. The roll 301 is intermittently driven to take up the material as it is woven and for this purpose its shaft 304 has fixed at the end thereof outwardly of the frame 2 a large gear 305 (see Figures 3, 5, and 7). Between the gear 305 and the frame 2 this shaft also carries a smaller gear 306 which meshes with a similar gear 307 fixed to rotate the roll 300. Both the rolls 300 and 301 are journaled in boxes as shown at 308 and 309 which are vertically slidable in guide recesses 310 formed in each frame 130

1 and 2, the upper box 308 being spring supported as shown at 311, on the lower box. The roll 302 is journaled in a bracket 312 fixed or integral with the front faces of the members 1 and 2. In order that the strands of fabric may not be crushed by passing over these rolls it is preferable to form the upper roll 300 fluted or longitudinally corrugated as shown at 313 in Figures 1 and 3. 10 the depressions of these corrugations coming opposite the lines of warp strands. This permits the filling strands, which are crimped by the alternate passing over and under the warp strands, to lie in these depressions so that they are not unduly compressed or injured, the fabric being engaged substantially uniformly across its width. 15 For the purpose of driving these rolls intermittently as above described, a ratchet mechanism has been provided, this being shown more particularly in Figure 5. Outwardly of the frame portion 2 the main shaft 315 carries an eccentric 315 having a strap 316 to which is attached an arm 317. 20 The outer end of this arm may be pivoted by a pin passed through any one of a plurality of holes 318 therein to the lower end of a bar 319. The upper end of this bar is fixed to an arm 320 which is pivoted on a shaft 321 25 journaled between side plates 322, 323 of a casing made fast to the end frame member 2. This shaft 321 has fixed thereon a ratchet wheel 324 and a pinion 325. The pinion 325 meshes with a gear 326 carried on a stub shaft 327 also journaled between the side plates 322 and 323 and which carries a pinion 328 meshing with the gear 305. It will thus be seen that rotation of the shaft 321 will impart rotation to the gear 305 and the 30 feed roll 301. Rotation of the shaft 321 is produced by oscillations of the arm 320, by means of a pawl 329, which is pivoted at 330 to the arm 320. While this pawl is so constructed as to tend by gravity to engage 35 the teeth of the ratchet wheel 324, such action may be insured by means of a spring 331 fastened at one end to the arm 320 and at the other to the rear end of the pawl. A gravity actuated pawl 332 positioned above 40 the ratchet wheel serves to prevent reverse rotation thereof. While adjustment of the throw of the pawl 329 may be effected by changing the point of connection of the link 317 to the bar 319, further adjustment is 45 also provided which may be actuated by the operator while the machine is in operation. This means comprises a bell crank member 333 pivoted on the shaft 321, one arm of 50 this lever extending over the teeth of the ratchet wheel 324 and furnishing a knock-off engaging the inner end of the pawl 329 on its retracting stroke and forcing it out of engagement with these teeth. The position of this arm angularly is determined 55 by means of a link 334 pivoted at one end

to the opposite arm of the bell crank and at its other end to an arm 335 fixed to a rock shaft 340. This rock shaft extends through the frame member 2 across the machine to a bracket 341 (see Figure 6) 70 positioned on the upper edge of the frame 1. This bracket 341 has an upstanding arched portion 342 flanged about its margin and having its upper segmental flange formed with notches on its edge as shown at 343. 75 Adjacent this bracket the shaft 340 has fixed an arm 344 terminating in a resilient handle portion 345 engageable in the notches 343. By this means the shaft 340 may be rocked and held in adjusted rocked position by engagement of the handle 345 in the notches 343, this serving to change the angular position of the pawl knock-off with relation to the swinging motion of the arm 320 to determine the extent of motion of the ratchet 80 wheel at each actuation of the arm 320. It will be noted that this control is at the left side of the machine readily accessible to the operator who may from the same point superintend the feeding of the filling 85 strand and control the main clutch. 90

The fabric take-up mechanism is claimed in my divisional application Serial Number 603,338, filed November 25, 1922, for take-up for looms. 95

The fabric is wound on an arbor 303, journaled at one end in a bracket 366 fixed to the front face of frame member 2, the other end of this arbor being removably fixed between jaws 367 outstanding from a bracket 368 made fast to the frame member 1. The arbor is held in position by means of a cotter pin 369. For the purpose of driving this arbor the shaft 304 outwardly of the gear 305 has a belt pulley 350 and the arbor 303 has a similar pulley 351 over which is passed a belt 352. The friction exerted between the belts and the pulleys may be adjusted by means of a tightening device comprising an arm 354 pivoted at 100 355 to a bracket member 366. This bracket has an outwardly extending flange 370 for receiving the pivot 355, the outer end of this flange being formed as a circular arc concentric with the pivot 355 and having teeth 105 371 thereon. The arm 354 carries a pawl 372 engageable with these teeth. At the upper end of this arm is carried a belt tightener pulley 373 which bears against the belt 352, the amount of tension thereon being 110 regulated by the position of the pawl 372 against the teeth 371. The lower end of the member 354 terminates in an actuating handle 374. 115

Having thus described certain embodiments of this invention it should be evident to those skilled in the art that many changes and modifications might be made therein without departing from its spirit or scope as defined by the appended claims. 125 130

I claim:

1. A pick laying means comprising a reciprocable bar having a strand channel therein, jaws reciprocably carried by said bar for gripping a strand in said channel, means actuatable to close and open said jaws by their reciprocation relative to said bar, and means actuated by the reciprocation of said bar for reciprocating said jaws relative thereto.
2. A pick laying means comprising a reciprocable bar having a strand channel, jaws for gripping a strand in said channel, a lever fulcrumed on said bar, connections from said lever to said jaws whereby said jaws are opened and closed by the rocking of said lever, and stops positioned adjacent the path of said bar against which said lever impinges to be rocked by continued motion of said bar after such impingement.
3. A pick laying means comprising a reciprocable bar having a channel for a strand therein, jaws tending to grip a strand in said channel, a wedge element carried by said bar and actuatable to open said jaws or to permit said jaws to close, and means actuatable when said bar approaches the limits of its reciprocation for actuating said element.
4. Pick laying means comprising a reciprocable bar, strand gripping jaws reciprocable with and relative to said bar, means actuatable to close and open said jaws by their reciprocation relative to said bar, and means actuated by the reciprocation of said bar for reciprocating said jaws relative thereto.
5. Pick laying means comprising a reciprocable bar, jaws movable with said bar for gripping a strand, a lever fulcrumed on said bar, connections from said lever to said jaws, whereby said jaws are opened and closed by the rocking of said lever, and stops positioned adjacent to the path of said bar and against which said lever impinges to be rocked by continued motion of said bar after such impingement.
6. In a loom, shedding mechanism, means for successively laying and cutting off from a strand of indeterminate length picks of 50 filling in the shed, and means for continuously feeding the strand to said means.
7. In a loom, shedding mechanism, means for carrying the end of a filling strand to a point intermediate the sides of the shed, 55 means for grasping the end of the strand so carried and drawing it the remaining distance through the shed, means for cutting off the strand beyond said carrying means when said grasping means is retracted whereby the end of the strand may be grasped for a succeeding carrying movement, and means for feeding said strand continuously to said carrying member.
8. In a loom, shedding mechanism, means 60 for carrying the end of a filling strand to a point intermediate the sides of the shed, means for grasping the end of the strand so carried and drawing it the remaining distance through the shed, means for cutting off the strand beyond said carrying means when said grasping means is retracted whereby the end of the strand may be grasped for a succeeding carrying movement, and means to produce a slack condition 65 of said strand adjacent said carrying means while it is retracted to prevent a sudden jerk thereon on a succeeding carrying movement.
9. A loom comprising shedding mechanism, 70 a pair of pick-laying members movable into the shed from opposite sides, one of said members presenting the end of a filling strand of indeterminate length to the other of said members to receive and 75 grip the same, whereby on subsequent retraction of said members a pick is laid, and means for cutting the strand adjacent said presenting member when said pickers are retracted, said presenting member having 80 means acting to retract the cut end thereinto and there retain it during the succeeding inward motion of the members and then to project it into position to be engaged by 85 said receiving member.

In testimony whereof I have affixed my signature.

EARL F. BALDWIN.
